RICHARD WHITAKER, JR., OF NEW BRUNSWICK, NEW JERSEY, ASSIGNOR TO MANUFACTURERS IRON & STEEL COMPANY, OF NEW BRUNSWICK, NEW JERSEY, A CORPORATION OF NEW JERSEY.

PLIERS.

1,346,392.

Specification of Letters Patent. Patented July 13, 1920.

Application filed March 8, 1919. Serial No. 281,462.

To all whom it may concern:

Be it known that I, RICHARD WHITAKER, Jr., a citizen of the United States, residing at New Brunswick, in the county of Middlesex and State of New Jersey, have invented a new and useful Improvement in Pliers, of which the following is a specification.

The present invention relates to an improvement in pliers, and more particularly to an improvement in side cutting pliers provided with removable or detachable cutters or cutting edges. One object of the invention is to improve upon the construction and arrangement of the parts of side cutting pliers provided with removable cutters in order to increase the efficiency and durability of the pliers, while at the same time enabling the cutters, when worn, to be quickly removed and replaced by a new pair. A further object of the invention is to construct the removable cutters in such form that the strains to which they are subjected while in use will have no tendency to loosen them in the recesses formed in the plier jaws for their reception. To the accomplishment of these objects, the invention consists in the improved pliers described and claimed in the following specification:

30 The preferred form in which it is at present contemplated embodying the invention is illustrated in the accompanying drawings, in which Figure 1 is a rear side elevation of the improved pliers in closed position; Fig. 2 is a front side elevation of the pliers in opened position; Fig. 3 is a section taken on the line 3—3 of Fig. 1; and Fig. 4 is a perspective of one of the removable cutters.

40 The improvement of the present invention is applicable to side cutting pliers of any usual or preferred form; the pair of pliers shown in the accompanying drawings being of the type known as linemen's pliers. 45 In pliers of this type, it is necessary to provide for a wide opening of the jaws and also a wide opening between the cutting edges or cutters of the pliers. It is also necessary that the cutting edges or cutters be located 50 as close as possible to the fulcrum of the pliers in order to secure the proper leverage. In pliers of this type there is also provided a square or rectangular opening or throat behind the cutting edges, so that the pliers 55 may be used by the lineman as a wrench for

loosening and tightening binding screws and contact terminals. These various essential features of a pair of linemen's pliers are present in the pliers illustrated in the drawings and the removable cutters of the present invention are so constructed as not to interfere either with the wide opening of the jaws or with the rectangular wrench-like opening behind the cutting edges.

The pliers as illustrated comprise two parts or sections 5 and 6, and each section consists of a jaw 7 and a handle 8 by which the jaws are manipulated. The plier sections are connected at 9 by a relatively large fulcrum and the parts of the pliers immediately adjacent the fulcrum are relatively heavy in order that the pliers may stand the heavy usage to which linemen and others subject this type of pliers. The cutting edges 10 of the pliers are, as is usual, located as near as is mechanically convenient to the fulcrum 9. The portions 11 of the jaws extending beyond the cutting edges 10 constitute the gripping part of the jaws and are of the full width of the pliers. From the point of junction 12 between the cutting edges 10 and the portions 11, however, toward the fulcrum, the jaws are recessed not only to provide for the cutting edges but also to provide a rectangular throat 13 (Figs. 1 and 3) which may serve the purposes of a wrench.

In the pliers as modified according to the present invention, the cutting edges 10 are formed, not on the plier jaws themselves, but on detachable cutter pieces 14 which are received and held in recesses formed in the front sides, or the opposing faces, of the jaws in such manner that the cutting edges of the cutter pieces will occupy the same relative position with respect to themselves and the other parts of the pliers that they would occupy if they were made integral with the plier jaws. It will be noted that the bases 17 of the cutter pieces are relatively thin and that their inner faces and their bottom faces are parallel throughout their entire width and that they are of substantially uniform thickness, except where the cutting edges are formed. The thin flat bases are of advantage in that they make it unnecessary to deeply recess the jaws of the pliers. Thus the strength of the jaws is preserved. In order that the cutter pieces 14 may not become loosened so as to fall out of their re-

cesses while the pliers are in use, each piece is provided on its base or bottom side with a flange or tongue 15 which is snugly received in a corresponding groove formed in 5 the end or forward part of the plier jaw, that is, that part of the plier jaw farthest away from the fulcrum. The cutter pieces are held against lateral displacement by means of screws 16 which pass through the 10 rear side of the cutter jaws and into the bases or bottoms 17 of the cutter pieces. The bottoms of the cutter pieces are of the same thickness as the flanges or tongues 15 for a substantial part of the width of the cutter 15 pieces as shown most clearly in Figs. 3 and 4. From about the point 18 (Fig. 4), the cutter pieces are provided with up-turned lips 19, and the upper edges 20 of these lips constitute the cutting edges of the cutter 20 pieces. By reason of the fact that the bases of the cutter pieces are flat on their opposing sides for more than half their width, a rectangular throat is formed when the jaws of the pliers are closed as shown in Figs. 1 and 25 3. This rectangular throat has the same dimensions and can be put to the same purposes to which the rectangular throats in the jaws of this type of pliers are put. This is by reason of the novel construction of the 30 improved detachable cutter pieces.

The above described construction of side cutting pliers is such that the cutting strain is not imposed upon the threads of the 35 screws which hold cutter pieces against lateral movement. This is of the utmost importance in side cutting pliers provided with detachable or removable cutters. A consideration of Fig. 3 will make it clear that if the cutter pieces were held in position by the 40 screws alone, the cutting strain would necessarily be communicated to the threads by reason of the fact that the cutting edges are situated at the outer edge at one side of the plier jaws. This is one reason why it has 45 been found heretofore highly unsatisfactory to provide side cutting pliers with detachable cutters. In former constructions of side cutting pliers provided with detachable cutters, the cutting strains and stresses, so far 50 as is known, have been imposed more or less upon the screws which hold the cutters in place, with the inevitable result that the cutters become loosened and, so, ineffective. The present construction of side cutting 55 pliers with detachable cutters eliminates these difficulties by absolutely removing all cutting strains from the screws. In fact, the only function performed by the screws is to hold the cutters against lateral movement, the whole of the cutting strain being

taken up by the tongues projecting laterally from the bases of the cutters and received in special grooves provided for their reception cut in the jaws themselves. This construction, moreover, enables a broken or worn out 65 pair of cutter pieces to be quickly and easily replaced by a new pair, for the reason that the threads of the screws are never injured and the tongues of the cutter pieces are heavy and strong enough to resist any twisting- 70 or breaking strains.

It will be understood that the invention is not limited to the precise form described above and illustrated in the drawings, but that it may be embodied in other forms 75 within the scope of the appended claims.

Having thus described the invention, what I claim as new is:—

1. A pair of side cutting pliers comprising a pair of jaws, handles by which the 80 jaws may be manipulated, a removable cutter for each jaw consisting of a thin flat base and a cutting edge formed at substantially right angles thereto, said base being of substantially uniform thickness except where 85 the cutting edge is formed and being prolonged at one side beyond the end of the cutting edge to form a tongue, and recesses in the opposed faces of the jaws to receive the cutters, each recess being provided with 90 a groove to receive the tongue of a cutter.

2. A pair of side cutting pliers comprising a pair of jaws, handles by which the 95 jaws may be manipulated, a removable cutter for each jaw consisting of a flat base and a cutting edge formed at substantially right angles thereto, said base having its inner 100 face and its bottom parallel throughout its full width and being extended at one side to form a tongue, and recesses in the opposed faces of the jaws to receive the cutters, each recess being provided with a groove to receive the tongue of a cutter.

3. A pair of side cutting pliers comprising a pair of jaws, handles by which the 105 jaws may be manipulated, a removable cutter for each jaw consisting of a base and a cutting edge formed at substantially right angles thereto, the inner face and the bottom of the base being parallel throughout the 110 width of the cutter and the base being extended laterally at one side beyond the end of the cutting edge to form a tongue, and recesses in the opposed faces of the jaws to receive the cutters, each recess being provided with a groove extending toward the 115 end of the jaws to receive the tongue of a cutter.

RICHARD WHITAKER, JR.
